GROUNDING DEVICE

Carl G. Bondeson, Terryville, Conn., assignor to
The Andrew Terry Company, Terryville, Conn.,
a corporation of Connecticut

Application July 15, 1933, Serial No. 680,600

5 Claims. (Cl. 247—1)

This invention relates to devices for grounding electrical systems and the conduits and apparatus employed therein.

An object of this invention is to provide a grounding device which is very easily and conveniently attachable to a water pipe or other grounding pipe or rod, and yet make a rigid, secure and good electrical connection with the grounding pipe or rod.

Heretofore, the fitting was secured to the grounding pipe by a fixed jaw and a loose jaw and two screws for securing the jaws together. With such devices, it was necessary to loosen the two screws and remove one of them from the fitting, then place the fixed jaw against the grounding pipe, then place the loose jaw and replace the removed screw in the fitting, and tighten up the two screws. According to the present invention, there are a fixed jaw and a movable jaw, but the movable jaw is carried by a single screw threaded in one leg of a U-shaped fitting, so that merely by running up the screw the space between the jaws is enlarged to permit the pipe to be inserted. After this has been done, the screw is run down and the jaws are tightly clamped against the grounding pipe.

Although the jaw is pivotally carried by the end of the adjusting screw, it is preferably held against turning so as to make it convenient to use, and this is accomplished by making one side of the jaw flat and having it arranged in position to engage the base of the U-shaped fixture.

Another object of this invention is to provide a fitting which is flexible between the two fixtures of which it is composed.

Heretofore, in grounding fittings, it was proposed to have two fixtures, one for engagement with the grounding pipe and the other for engagement with the ground wire conduit and to have these two fixtures rotatably connected together. According to the present invention, this may be done when convenient. However, on occasions it is not convenient, especially when the conduit pipe for the grounding wire is cut too short or cannot be brought close to the grounding pipe. When this condition exists, according to the present invention the two fixtures may be separated and a wire or, as is preferred, a heavy ribbon or strap may be employed to connect the two fixtures. When this is done, the rotatable adjustment of the ground pipe engaging fixture is maintained and yet the connecting member between the two fixtures may be bent to change the angular relation between the fixtures or their distance apart.

A further object of this invention is to provide a ground pipe engaging fixture which, when connected to a like fixture by a suitable conductor, may be used to shunt around meter boxes, etc., and form a good electrical connection between pipes entering and leaving the meter box.

Another object of this invention is to provide a ground pipe engaging fixture which may be connected to a grounding wire conduit, or the flexible connecting strap above referred to, or the jumper wire last referred to, at either of two places located at right angles with relation to each other so that if it is more convenient the conduit fixture strap or jumper may be secured either to the portion of the U-shaped member which constitutes its base or that portion which constitutes the leg of the U having the solid jaw.

Other features and advantages will hereinafter appear.

In the accompanying drawings—
Figure 1 shows the present invention applied to a rigid ground fitting.

Fig. 2 shows two ground pipe engaging fixtures, of the kind shown in Fig. 1, connected together by a jumper and constituting a meter shunt.

Fig. 3 shows the grounding pipe fixture and the conduit and ground wire fixture separated but connected together by a flexible member.

Fig. 4 is a plan view of the conduit pipe fixture shown in Figs. 1 and 3.

Fig. 5 is a front view of the ground wire fixture.

Fig. 6 is a modification of the device shown in Fig. 3.

In the form of the invention illustrated herein, which is the form at present preferred, the fixture 10 is intended to grip the grounding pipe or rod while the fixture 11 is intended to receive the conduit containing the grounding wire. For this purpose, the fixture 11 is provided with a threaded collar 12 in which the ground wire conduit is threaded. The fixture 11 has a table-like portion 13 onto which the grounding wire issuing from the pipe may be placed to be secured in place under a lug 14 or other suitable device. If desired, the grounding wire may be soldered in the lug 14. The table-like portion 13 has projections 15 which hold the lug 14 from turning.

The grounding fixture, according to the present invention, is U-shaped and has opposite legs 16 and 17 and a cross or base member 18. The leg 17 has a V-shaped clamping jaw 19 provided with serrations or teeth 20 adapted to engage and bite into the grounding pipe.

Heretofore, the jaw cooperating with the fixed

5 jaw was made separable and was provided with a pair of screws, one on each end, to draw the movable jaw toward the fixed jaw. In order to apply the grounding fixture to the grounding pipe, it was therefore necessary to loosen both of the screws and completely remove one of the screws so as to allow the pipe to pass in between the jaws. Then the removed screw had to be 10 replaced and the two screws drawn up more or less evenly to clamp the movable jaw on the pipe opposite the fixed jaw. In some instances, this was found inconvenient, especially where the grounding pipe was located in a hole or well.

15 According to the present invention, the necessity of removing a screw from the grounding fixture is completely obviated and the movable jaw is always held in position to properly engage the grounding pipe.

20 To accomplish this, the present invention has a movable jaw 21, also V-shaped, and having teeth 22, and this jaw is rotatably carried on the end of a screw 23 which is threaded into the leg 16 of the grounding fixture so that by rotating the screw the jaw 21 will be moved toward and 25 from the jaw 19. The distance between the legs 16 and 17 is such that any size pipe over a large range for which the device is designed may be inserted between the jaws.

20 To hold the jaw 21 in proper position to engage the pipe, the side 24 thereof is made flat and so is the surface 25 of the base of the U. Hence, these substantially flat surfaces will engage when the jaw 21 tends to rotate and the rotation of the jaw will be restricted so that the jaw 21 never 35 becomes so much out of alignment that the jaw 19 has to prevent the jaw 21 from seating itself securely on the pipe when the screw 23 is turned down.

30 The apexes of the V-shaped jaws 19 and 21 are offset or displaced so as to apply a greater portion of the pressure to the inner part 19a of the jaw 19 rather than the weaker outer part 19b, and so as to tend to cant the screw 23 in the threaded aperture 26 in the leg 16 and thereby 45 avoid loosening of the screw by vibration and obviate the need for a lock nut on the screw.

35 As shown in the accompanying drawings, the fixture 10 is provided with a cylindrical boss 27 and the fixture 11 is provided with a recess to receive the boss. Concentric with the boss 27, the fixture 10 has screw-threads 28 and when the fixtures 10 and 11 are to be secured together as 40 shown in Fig. 1, a screw 29 passes down through the table-like portion of the fixture 11 into the screw-threaded portion 28 of the fixture 10 and holds the two fixtures together. When the screw is loosened, the fixtures may rotate relative to 50 each other to change their angular position.

45 The screw 29 also passes through the lug 14 and holds the lug and the grounding wire when the latter is placed under the lug or is soldered to the lug in firm and good electrical connection with the fixtures.

55 It is usually most convenient to have the fixtures 10 and 11 united as shown in Fig. 1, with the screw 29 at right angles with relation to the screw 23. However, occasionally it is more convenient to have these screws arranged in parallel planes, and thus, according to the present invention, the leg 17 of the U is provided with a boss 27a and a screw-threaded hole 28a to receive the fixture 11 and screw 29.

60 In some situations, it is impossible to bring the fixtures 10 and 11 into such close proximity that they can directly engage each other as

6 shown in Fig. 1. In this case, the fixtures 10 and 11 may be connected together by a flexible strap 30 as shown in Fig. 3. This may be secured in place under the lug 14 by the head of a bolt 31 passing through the fixture 11 and having at its opposite end a nut 32. The opposite end of the strap 30 may be secured to the fixture 10 by a screw 33 engaging the threads 28 or 28a as desired. The end of the strap under the bolt 30 may be held on the fixture 11 against turning 10 by nibs 34.

15 At the end attached to the grounding pipe fixture 10, however, the rotatable relation between the fixture 10 and part to which it is connected is maintained so that it may be adjusted to meet 15 the particular angle at which the grounding pipe happens to be located. If, in making the installation, the ground wire conduit should be too short to permit the fixtures 10 and 11 to be united as shown in Fig. 1, they may be separated and the 20 strap 30 inserted between them. If other pipes or obstructions prevent the uniting as in Fig. 1, again the strap 30 may be inserted between them and it may be bent in any way desired to avoid any obstruction that may be present.

25 The device of the present invention may, as shown in Fig. 6, be made up originally for the service for which the device shown in Fig. 3 is intended. In this event, as shown in Fig. 6, the table-portion 13 may be reduced in size and may 30 be provided with a threaded hole to receive a screw 35, and in this form the lug 14 is omitted because the grounding wire may be placed directly under the strap 30. In the forms shown in 35 Figs. 3 and 6, the nibs 34 are four in number and are so placed that the strap 30 may extend and be held in alignment with the conduit pipe or at right angles thereto in either direction.

The fixture 10 of the present invention may 40 also be advantageously employed in connection with meter shunts. When used for this purpose, two fixtures 10 are employed as shown in Fig. 2. The fixtures 11 are laid aside and the lugs 14 are placed directly under screws 36 which may be threaded in the holes 28 or 28a as desired. The 45 lugs have soldered to them a jumper 37 and, in use, one fixture 10 is secured to the pipe entering the meter box while the other fixture is secured to the pipe leaving the meter box, so as to complete a grounding connection around the meter.

50 Variations and modifications may be made within the scope of this invention and portions of the improvements may be used without others.

Having thus described the invention, what is claimed as new and for which it is desired to obtain Letters Patent, is:—

55 1. A ground fitting comprising a fixture; means on the fixture for receiving a grounding conductor; a V-shaped jaw solid with said fixture and adapted to engage one side of a grounding pipe or rod; a movable V-shaped jaw opposite the first-named V-shaped jaw; and a screw carrying said second V-shaped jaw and threaded in the fixture to advance or retrieve the movable V-shaped jaw, the apexes of the V-shaped jaws being offset with relation to each other.

60 2. A ground fitting comprising a fixture; means on the fixture including a bendable current-conducting member mechanically and electrically connecting a grounding wire to the fitting; a V-shaped jaw solid with said fixture and adapted to engage one side of a grounding pipe or rod; a movable V-shaped jaw opposite the first-named V-shaped jaw; and a screw carrying said second V-shaped jaw and threaded in the fixture to ad-

vance or retrieve the movable V-shaped jaw, the apexes of the V-shaped jaws being offset with relation to each other.

3. A ground fitting comprising a U-shaped fixture; means on the fixture including another fixture having a table-like portion to receive a grounding conductor and a threaded collar to receive a conduit and adapted to be secured to the first fixture for mechanically and electrically connecting the grounding wire thereto; a V-shaped jaw solid with said first fixture forming one leg of the U and adapted to engage one side of a grounding pipe or rod; a movable V-shaped jaw opposite the first-named V-shaped jaw; and a screw carrying said second V-shaped jaw and threaded in the other leg of the U to advance or retrieve the movable V-shaped jaw, the apexes of the V-shaped jaws being offset with relation to each other.
- 10 4. A ground fitting comprising a U-shaped fixture; means on the fixture including another fixture mechanically and electrically connected to the first fixture by a bendable current-carrying member; a V-shaped jaw solid with said first

fixture forming one leg of the U and adapted to engage one side of a grounding pipe or rod; a movable V-shaped jaw opposite the first named V-shaped jaw; and a screw carrying said second V-shaped jaw and threaded in the other leg of the U to advance or retrieve the movable V-shaped jaw, the apexes of the V-shaped jaws being offset with relation to each other.

5. A ground fitting comprising a fixture; means on the fixture including another fixture having a conduit-receiving portion and a conductor-receiving portion mechanically and electrically connected to the first fixture by a bendable current-carrying member secured to the first fixture by a binding screw to ground the same thereto; a V-shaped jaw solid with said first fixture and adapted to engage one side of a grounding pipe or rod; a movable V-shaped jaw opposite the first-named V-shaped jaw; and a screw carrying said second V-shaped jaw and threaded in the fixture to advance or retrieve the movable V-shaped jaw, the apexes of the V-shaped jaws being offset with relation to each other.

CARL G. BONDESON.
